United States Patent Office

Des. 196,835
Patented Nov. 12, 1963

196,835

MOTOR VEHICLE

Frederick W. Herbst, Woodmere, and Daniel R. Herbst,
Hewlett, N.Y., assignors to The Vendmobile Corpora-
tion, Hempstead, N.Y., a corporation of New York

Filed Jan. 15, 1962, Ser. No. 68,314

Term of patent 14 years

(Cl. D14—3)

FIGURE 1 is a rear perspective view of a motor vehicle showing our new design; and

FIGURE 2 is a fragmentary front perspective view thereof.

The dominant features of our design reside in the portions shown in full lines. The drawing is lined to represent color contrasts.

We claim:

The ornamental design for a motor vehicle, as shown and described.
